UNITED STATES PATENT OFFICE

BENJAMIN JAY STEINMETZ, OF NEW YORK, N. Y.

VENTURI SLOT FOR AEROPLANE WINGS

Application filed July 25, 1929. Serial No. 380,851.

This invention relates to improvements in aeroplanes and more particularly to the wing construction thereof, whether cambered or plain, and as used in connection with planes having one or more pairs of wings.

It is an established fact that the area upon the upper surface of a wing in flight is an area of reduced or negative pressure and it is that partial vacuum that sustains a plane while it is in rapid motion; it is this sustaining lift which must be maintained until the plane alights.

In the conventional plane it is necessary to maintain a speed of at least 40 to 50 miles per hour to create a sufficiently evacuated area upon the upper surface of the wings to enable the plane to fly. This speed makes it difficult for a plane to easily arise from or descend upon any but specially prepared and lengthy flying fields and none but an extremely skillful aviator can land a plane at high speed without mishap.

When a plane tilts upward the wings lose their normal lift. In their inclined state the air that passed over them in a smooth even stream becomes a whirling eddy which frustrates the effect of a partial vacuum, and so the lift breaks down and the plane loses its sustaining support and falls out of control to inevitable catastrophe.

It is therefore the object of the present invention to provide means for producing an additional and constant suctional effect by the action of the rush of air upon the under surface drawing the air from the upper surface through slots provided in a novel manner and used to create a greater vacuum at both high and low speed, enabling a plane to carry a much greater load than upon wings of like area without the use of the present invention, and particularly to enable a plane to maintain its necessary lift upon alighting and taking off at a very low rate of speed.

Also by the use of this device an aeroplane, when in an inclined state instead of the wings losing the supporting lift, by the eddying currents formed upon its upper surface, maintain the flow evenly and with con-

tinued lifting power, enabling the plane to fly without danger of mishap to its occupants.

A further feature is in the provision of means for attaining the foregoing object which are simple in their application, practical in operation, readily controllable and easy to apply.

These objects are accomplished by the novel construction and arrangement of parts hereinafter described and illustrated in the annexed drawing, forming a material part of this disclosure, and in which:—

Figure 1 is a perspective view of a conventional type of monoplane, looking from the under side, showing an adaptation of the invention.

Figure 2 is a transverse sectional view of a wing illustrating an application of the improvement.

Figure 3 is a fragmentary side elevation of the body of the machine, showing an automatic means of plane wing vent control.

As shown in the drawing, the body or fuselage of the machine, designated by the numeral 10, is provided with landing gear including wheels 11 and driven by a propeller 12 at the front as usual.

At the rear are horizontal rudders 13 and a steering rudder 14, while extending from the sides, over the top, are wings 15, all of which form no part of the present invention, which relates exclusively to controllable means for reducing the air pressure on top of the wings and increasing the compression therebelow.

This is accomplished by forming elongated ducts 16 through the wings, extending approximately from the ends to the body and inclined downwardly towards the rear from the top at an angle in advance of the ailerons, the position being preferably remote from the advancing edge and parallel with it.

Fixed adjacent the rear edge of the ducts 16, at their ends, are brackets 17 extending below the wings the same being given a stream line effect, and attached rigidly to the brackets are plates 18 extending below

the ducts and reaching forwardly so that their front edges extend in advance.

Hinged to these front edges, as at 19, are plate deflectors 20 extending towards the front and controlled by links 21 at their forward end edges, the links reaching upward through the lower walls of the wings to be pivotally connected with levers 22 fixed on a shaft 23 extending lengthwise

10 through the wing structure.

Fixed on the shaft 23 is a gear wheel 24 meshed with a worm 25 directly driven by the shaft 26 of a pinion 27 rotatable within the wing structure and actuated by a rack 15 28 slidable in a horizontal plane transversely within the wing structure, preferably along its lower surface.

The rack 28 is actuated by a rod 29 projecting through the front or leading edge 20 of the wing and urged outwardly by the action of a spring 30.

Fixed to the extending end of the rod 29 is a vane 31 preferably disposed at the center of the wing and curved upwardly 25 in conformity with the leading edge of the wing which it abuts under pressure of the air when the machine is advancing at a high rate of speed, thereby changing the inclination of the deflector and its Venturi effect.

30 Obviously more than one vane may be employed and vanes may be adjusted relatively in a manner to raise and lower the deflector at will, thus controlling the suctional effect through the duct 16, the device 35 partaking of the nature of a venturi in its action on the air, and is entirely automatic in its action.

From the foregoing it will be seen that when the deflector 20 is in its operative position it will produce a suctional effect, tending to draw the air downwardly through the inclined ducts 16 in the manner described and when parallel with the wing substantially no obstruction is present.

40 Although the improvements have been described with considerable detail and with respect to certain particular forms of the invention, it is not desired to be limited to such details since many changes and modifications may well be made without departing from the spirit and scope of the invention in its broadest aspect.

Having thus described the invention, what is claimed as new and desired to secure by 55 Letters Patent, is:—

1. An aeroplane wing having a duct extending lengthwise through its rear portion the walls of the duct being inclined rearwardly at an angle to the upper face of 60 the wing, a fixed plate spaced below the duct, a deflector plate hinged to the front edge of said fixed plate to extend forwardly, and automatic means for varying the inclination of said deflector plate.

65 2. An aeroplane wing having a duct ex-

tending lengthwise through its rear portion the walls of the duct being inclined rearwardly at an angle to the upper face of the wing, a fixed plate spaced below the slot, a deflector plate hinged to the front edge of 70 said fixed plate, mechanical means for raising and lowering said deflector plate, and automatic means operable from below the wing to actuate said mechanical means.

In testimony whereof I affix my signature. 75
BENJAMIN J. STEINMETZ.
